(57) CLAIM

The ornamental design for a utility knife, as shown and described.

DESCRIPTION

FIG. 1 is a top perspective view of a utility knife according to a first embodiment of our new design;

FIG. 2 is a left side elevation view of the utility knife of FIG. 1;

FIG. 3 is a right side elevation view of the utility knife of FIG. 1;

FIG. 4 is a front elevation view of the utility knife of FIG. 1;

1 Claim, 4 Drawing Sheets
